PACKAGE FOR PLASTIC MATERIALS

Edward B. Ekdahl, Irvington, N. J., assignor to
Sefco Inc., Newark, N. J., a corporation of New
Jersey

Application June 22, 1935, Serial No. 27,843

13 Claims. (Cl. 221—60)

This invention relates to a new and improved form of package for pastes or plastic materials, more particularly food stuffs of this character.

An object of the invention is to provide a cap for a collapsible tube or the like having associated therewith an extrusion nozzle through which the material may be extruded in a desired shape.

One feature of my invention is the provision of a package arrangement including a plurality of extrusion nozzles having variously shaped orifices, and arranged so that any one or combination of two or more nozzles may be used at one time in a simple, efficient and sanitary manner.

It is frequently desirable in the use of certain processed plastic foods such as pastes of cheese, fish, or meat, or sugar icings and the like to apply these materials to a surface of some other food material such as crackers, pastry or bread in a decorative extruded form.

In a package according to my invention several types of nozzles may be included with a collapsible container as sold, and the user may then simply open the package and remove the nozzles which are not to be used. Upon leaving or replacing the selected nozzle one may directly squeeze the material from the collapsible container in the desired extruded shape.

Further features and advantages of my invention will be readily apparent from the following description of the embodiments illustrated in the drawing, in which:

Figure 1 is a longitudinal section through the center of the discharge end of a package as prepared for sale.

Figure 2 is a similar view through a package which has been opened and is ready for use.

Figure 3 is a plan view of an extrusion nozzle having a round orifice.

Figure 4 is a plan view of another nozzle adapted to extrude a crinkly ribbon of material.

Figure 5 is a plan view of a nozzle having another form of orifice.

Figure 6 is an end elevation of a package showing a fourth extrusion nozzle in operative position to extrude a ribbon shaped length of material.

Figure 7 is a view similar to Figure 1 showing another embodiment of my invention in which the extrusion nozzles are simply disc shaped, and

Figure 8 is a view similar to Fig. 2 showing a disc shaped extrusion nozzle in operative position.

My invention is preferably applied to an ex-

truded collapsible tube 10 formed of tin, aluminum, or the like and having a neck portion 11 which is threaded on the outside to receive a cap 12. Instead of using a cap as the sealing means for the opening in the neck 11, my improved cap has an opening 13 in its top to receive the crowns of a series of cup shaped extrusion nozzles 14.

In the preferred embodiment of my invention these extrusion nozzles are arranged in sets 10 adapted to be nested together as shown in Fig. 1. Each nozzle preferably has an opening of different shape such as shown in Figs. 3 and 6. It will be understood that these openings may be of any desired configuration. The neck of the collapsible tube may be provided with a sealing partition 15 at its end formed thereon in the course of extruding the tube. When the package is to be used, the cap and extrusion nozzles 14 are removed and this partition 15 is then punctured with some sharp instrument, such as an ice pick. The extrusion nozzle 14 having the desired shape of opening may then be fitted into the cap and the cap replaced on the neck 11. The plastic food or the like may then be extruded 20 through the orifice in the selected extrusion nozzle by simply squeezing the collapsible container 10.

In initially assembling the package, I prefer to include a plain disc 16 which may be used to 30 seal the opening in the partition 15 after this partition has been punctured. After the package has been used to extrude some of the material therein, it is a very simple matter to rinse the extrusion nozzles, if necessary, and replace 35 them, together with the plain disc 16, in the cap 12 which is then screwed on in place. If desired, the partition 15 might be provided originally with an opening and the disc 16 would then be relied upon to effect the seal as the package is 40 shipped. If the openings in nozzles 14 are of suitable configuration to jointly close the opening in the cap completely, the disc 16 may be omitted.

By comparison of the crowns or cup shaped 45 portions 17 of the extrusion nozzles shown in Figs. 2-6 it will be apparent that these portions are of varying diameter, with the flange portions 17a also varying in size in accordance with the diameter of the respective cup portions, thus providing for assembly as shown in Fig. 1. It should be noted, however, that the cup shaped portions of the several extrusion nozzles are of the same depth. Thus, when one nozzle is used alone, it always projects a slight distance beyond the outer 55

face of the cap 12 (Fig. 2). By providing nozzles of this shape the extruded paste strip is positively prevented from contacting the outside of the cap during use.

5. These extrusion nozzles may be made of metal, such as tin, aluminum and the like, or other material by a simple stamping operation which forms the cup shape portions 17 and the orifices in a single step or they may be made in any 10 other convenient manner.

While the extrusion nozzles are shown with flanges at right angle to the walls of the cup shaped portions, the latter may be tapered inwardly from the former so that these various 15 nozzles may be made to nest even though they are of the same size. Such an arrangement, however, is likely to cause the different nozzles to wedge together if the cap should be screwed too tightly in place and therefore the form illustrated 20 is preferred.

Another embodiment of my invention is illustrated in Figs. 7 and 8 for use with a tube 10 having a neck 11 which is formed without the integral closure or partition 15. In this embodiment of my invention I employ simple flat disc-shaped extrusion nozzles 18. Any desired number of these flat discs 18 may be employed with or without a sealing disc 16. The use of these modified containers will be substantially the same 25 as described above. The flat nozzles are not so satisfactory when the tubes are closed by the partitions 15 since no space is then provided between the irregular opening punched in the partition and the opening intended to control the 30 design. The provision of such a space, as in Fig. 2, insures proper formation of the extruded strip without particular care in puncturing the partition.

If desired the form of the openings in the various 40 nozzles may be such that artistic configurations will be produced not only by the individual nozzles but also by combination of two or more nozzles. Thus provision may be made for a greater number of designs than the nozzles provided. Furthermore, two or more nozzles may fit 45 together in different positions to produce different designs. Whenever it is desired to arrange the nozzles in definite relations they may be provided with interfitting projections and recesses, as by 50 indenting a portion of the wall of each nozzle.

It is also possible to practice my invention, in part, by means of separate and individual extrusion nozzles which may be threaded so that they may be screwed on the neck 11 in place of 55 the cap or by employing caps for the package in which the openings 13 are shaped to provide the desired extruded form of material.

The terms and expressions which I have employed are used as terms of description and not of 60 limitation, and I have no intention, in the use of such terms and expressions, of excluding any equivalents of the features shown and described or portions thereof, but recognize that various 65 modifications are possible within the scope of the invention claimed.

What I claim is:

1. In combination with a collapsible container for plastic material having a body portion and a neck, a cap for said neck, and a relatively inflexible nozzle member removably held in substantially fixed relation to said neck by said cap.
2. An article of manufacture comprising a collapsible extruded tube including a body portion and a neck portion, substantially rigid means 70 movably associated with said neck portion to

shape plastic material as it is forced out through said neck portion and a cap for holding said means in place.

3. An article of manufacture comprising a collapsible extruded tube including a body portion 5 for holding a plastic material and a neck portion, a cap, and substantially rigid, inflexible means held in engagement with said neck portion by said cap to shape the plastic material in a predetermined manner as it is forced out through said 10 neck portion.

4. An article of manufacture comprising a collapsible container for plastic material including a body portion and a neck portion, a cap, and a plurality of extrusion nozzle members held in 15 engagement with said neck portion by said cap.

5. An article of manufacture comprising a collapsible container for plastic material including a body portion and a neck portion, a cap, a plurality of substantially rigid extrusion nozzle members 20 held in engagement with said neck portion by said cap and means for sealing the neck portion.

6. An article of manufacture comprising a collapsible extruded tube including a body portion 25 and a neck portion, a cap having an opening in the top thereof, and a rigid nozzle held in engagement with said neck by the cap, said nozzle having an opening adapted to register with the opening in said cap for uniformly shaping plastic material 30 passing therethrough.

7. An article of manufacture comprising a collapsible container for plastic material including a body portion and a neck portion, a cap having an opening in the top thereof, and a relatively inflexible nozzle member held in engagement with 35 said neck by the cap, said member comprising a cup shaped section having a flange at the edge thereof with an opening in the cup portion adapted to register with the opening in said cap. 40

8. An article of manufacture comprising a collapsible container for plastic material including a body portion and a neck portion, a cap having an opening in the top thereof, and a nozzle held in engagement with said neck by the cap, said nozzle 45 being rigid and comprising a cup shaped section having a flange at the edge thereof, said cup section having an opening therein and being sufficiently deep to extend through the opening in said cap when assembled in operative position 50 therewith.

9. An article of manufacture comprising a collapsible container for plastic material including a body portion and a neck portion, a cap having an opening in the top thereof, and a set of substantially inflexible nested nozzle members held 55 in engagement with the neck by said cap.

10. An article of manufacture comprising a collapsible container for plastic material including a body portion and a neck portion, a cap having an opening in the top thereof, and a set of nested nozzle members held in engagement with the neck by said cap, said set of nozzle members having cup shaped portions adapted to fit into 60 each other and into the opening in said cap. 65

11. An article of manufacture comprising a collapsible container for plastic material including a body portion and a neck portion, a cap having an opening in the top thereof, and a plurality of extrusion nozzles held in engagement 70 with the neck by said cap, said nozzles being disc shaped and having variously shaped openings therein adapted to register with the opening in said cap.

12. An article of manufacture comprising a 75

2,103,111

collapsible container for plastic material including a body portion and a neck portion, a cap having an opening in the top thereof, a plurality of extrusion nozzles held in engagement with the neck by said cap, said nozzles being disc shaped and having variously shaped openings therein adapted to register with the opening in said cap and a disc shaped sealing member between said cap and the neck of said container.

5 13. An article of manufacture comprising a collapsible container for plastic material including a body portion and a neck portion, a cap having an opening in the top thereof, a set of substantially inflexible nested nozzle members held in engagement with the neck by said cap and means between said cap and said neck to seal the container. 5

EDWARD B. EKDAHL.
